UNITED STATES PATENT OFFICE

WALTER P. COUSINO, OF DETROIT, MICHIGAN

CARBURETOR AIR CONTROL

Application filed December 2, 1926. Serial No. 152,237.

This invention relates to the control of the air supply into the fuel of the carburetor.

This invention has utility when incorporated, in addition to and between the choke and throttle of a carburetor, to be controlled by the starter.

Referring to the drawings:

Fig. 1 is a fragmentary view of an embodiment of the invention in connection with an internal combustion motor propelled vehicle;

Fig. 2 is a view on an enlarged scale of the device with its wiring connections shown diagrammatically;

Fig. 3 is a section on the line III—III Fig. 2; and

Fig. 4 is a section on the line IV—IV Fig. 2.

The vehicle is shown as having foot board 1 with push starter switch 2 for connecting line 3 from battery 4 to line 5 extending to starting motor 6 for actuating internal combustion engine 7 herein shown as of the piston and cylinder type, thereby acting through intake manifold 8 past throttle 9 for inducing draft or suction upon carburetor 10 having a fuel supply or intake 11.

The motor 6 has therefrom line 12 to ground to complete circuit with line 13 to ground from the opposite side of the secondary battery 4. Throttle 9, as provided with arm 14, has connection 15 therefrom extending for convenient operation by the driver of the vehicle. Air cleaner 16 is shown as mounted on air supply duct 17 extending past choke 18 to chamber 19 of the carburetor 10 below which is reservoir 20 having enveloping electric coil 21 connectible by line 22 and switch 23, adjacent the driver of the vehicle, to permit turning of current into this coil 21 so that this chamber 20 serves as a heater for vaporizing any liquid fuel which may not be carried up past the throttle 9, in which liquid state it settles back down into the carburetor 10 to flow into this chamber 20.

In this invention, this chamber 20 of the fumer or heater device for the carburetor has air connection thereto shown as embodying L-fitting 24 with depending tube 25 therefrom. This tube 25 is preferably non-magnetic or not of a character to form a permanent magnet. It has solenoid winding or

coil 26 thereabout placed in circuit by switch 2 in parallel with the starting motor 6 by line 27. This tube 25 as connected with the fitting or L 24 has shoulder or seat 28 at chamber 29 in which is disposed iron or steel ball 30 ⁵⁵ precluded from lodging in the fitting 24 by guard wire 31.

In operation, the driver of the vehicle may open the throttle 9 and close the choke 18 provided with arm 33 and manually controllable extension 34 extending to a location convenient for operation by the driver. The driver may then step on the starter switch 2 to cause reciprocating engine 7 to act as a pump in developing suction in the carburetor 10 for drawing liquid fuel, as gasoline, from float chamber 35 as supplied by line 36.

At this condition for starting with the throttle open and the choke closed there is suction to such extent developed in the carburetor 10 as to pull a volume of the liquid fuel into the carburetor 10. The stepping on the starter switch 2 is generally for a brief interval, while the driver of the vehicle is prone to leave the choke closed for a period of time until the motor seems to warm up. This develops a flooded condition in the carburetor, especially acute when the starter switch 2 is opened.

This difficulty is automatically eliminated ⁸⁰ hereunder by the device of this disclosure. During the operating of the starter by closing the switch 2, the solenoid coil 26 is energized to increase the gravity holding action or seating of the ball 30 as thus magnetized. After suction becomes excessive in the carburetor 10 the design of the coil 26 is such that flooding of the carburetor may be avoided by the inflow of air through the tube 25 and L-fitting 24 into the reservoir 20 to the carburetor 10. This will check the flooding tendency of the fuel intake as well as supply air for combustion of such fuel in the motor 7. When the driver of the vehicle takes his foot off the switch 2, thus opening the circuit of the starting motor 6 to stop such motor from being operated by the storage battery 4, the coil 26 is deenergized and there is but a very much reduced holding action for retaining the ball 30 seated in closing off air sup- ⁹⁵ ¹⁰⁰

ply by way of the tube 25. Accordingly notwithstanding that the choke 18 may still be closed, there is retention of a degree of suction for fuel intake into the carburetor 10 which, when sufficient to unseat the ball 30, provides for combustion supporting air supply to mingle with the fumes of the flood of gasoline or fuel which may have condensed and settled into the chamber 20. Even after switch 23 be opened, this device will operate as an auxiliary air supply for assisting in starting and improving starting conditions, especially in cold weather. The opened device may coact in running conditions of the motor as an auxiliary air supply for assisting in more complete combustion of the fuel. With the choke open there is materially greater difficulty in unseating the ball 30 for such auxiliary air supply even though only temporarily magnetic.

This device is of material value in avoiding difficulty from flooding the carburetor in starting, as well as improving cold weather starting especially in the winter season.

25 In the event it is desired to minimize or avoid chatter and not use a spring on the ball 30, the sleeve 25 may be of magnetizable material, say weakly permanent. In such event, especially, it is preferable that the fitting 24 be non-magnetizable.

What is claimed and it is desired to secure by Letters Patent is:

1. A carburetor having an air supply, a normally closed closure therefor operable by motor suction draft in the carburetor, and a solenoid acting upon said closure for resisting opening thereof.

2. A carburetor having an air supply duct, a magnetizable ball closure for the duct, and a coil about said duct for acting upon said ball as an armature for affecting closing of said duct.

3. In combination, an internal combustion motor, a carburetor for supplying fuel thereto having a normal air intake and an auxiliary air intake, said auxiliary intake being provided with a normally closed closure openable by suction through the carburetor, a switch, and a solenoid energized through said switch operable for maintaining the closure in auxiliary intake closing position coincident with motor starting.

In witness whereof I affix my signature.

WALTER P. COUSINO.
